UNITED STATES PATENT OFFICE.

SCHUYLER H. EARL, OF ROCHESTER, NEW YORK, ASSIGNOR TO GLEASON WORKS, OF ROCHESTER, NEW YORK, A CORPORATION OF NEW YORK.

GEAR-GENERATING MACHINE.

Application filed October 4, 1924. Serial No. 741,582.

The invention relates to gear cutting machines, and more specifically to the tool mechanism of such machines.

One of the objects of this invention is to provide means whereby a change in the pressure angle of the gear to be generated may be effected by movement of the tool alone.

A further object is to provide means whereby movement of the tool, which represents a tooth of the basic member of the system on which the blank rolls, will effect a result equivalent to a change in the ratio of roll between the members controlling the relative movement of the tool and bank.

A preferred embodiment of my invention is illustrated in the accompanying drawings, in which:—

Figure 1 is a view in front elevation of the tool mechanism of a gear cutting machine provided with my invention;

Fig. 2 is an enlarged front elevation of the tool support;

Fig. 3 is a section on the line 3—3 of Fig. 2;

Fig. 4 is a plan view partly in section of a gear cutting machine of the type to which my invention may be adapted;

Fig. 5 is a perspective view of the wedge used to adjust the tool;

Fig. 6 is a diagrammatic view showing how the pressure angle may be changed by an adjustment of the tool; and

Figs. 7, 8 and 9 are sectional views showing various adjusted positions of the tool.

The invention is particularly pertinent to gear cutting machines of the generating type, in which a planing tool is employed to generate gear teeth on a gear blank by the relative movement of the tool and blank, and it is in connection with such a machine that my improvement is illustrated.

The relative motion between the tool 1 and the blank 2 may be effected by any suitable means. In the form of machine illustrated, the tool is reciprocated across the face of the blank by mechanism of any desired type, such as that shown, for instance, in the co-pending application of James E. Gleason, George H. Bryan, Eyyvind Finsen and Alton P. Slade, Ser. No. 624,962, filed March 14, 1923, and the blank is given a combined motion of rotation and translation whereby to roll the blank rela-

tively to the tool, the blank support, which is fixedly secured to a segment 6 which rolls on a segment 7 fixedly secured to the frame, being adjustably mounted in a cradle 3 which oscillates in guideways 4 in the frame 5.

Means (not shown) are provided for oscillating the cradle and the movement of the cradle causes the segment 6 to move on the segment 7, giving the blank the desired rolling or generating motion. The segment 7 65 may be a portion of a crown gear in which case the segment 6 would represent a section of the gear to be cut, or both segments 6 and 7 may be bevel gear segments as described in the co-pending application above 70 referred to.

When it is desired to change the ratio of roll or relative motion between the tool and blank, it has heretofore been necessary to either substitute a new segment for the segment 7 or to provide some means of adjustment for the latter segment. Variations in the pressure angle of the blank being cut from the desired pressure angle, due to unavoidable errors in the machine, could only 80 be corrected in the same way. I have discovered, however, that by tilting the tool angularly with reference to the face of a tooth of the blank to be cut variations in the pressure angle can readily be corrected and 85 an adjustment of the pressure angle made possible, so that the provision of a multiplicity of gear segments for each machine is rendered unnecessary and the loss of rigidity, which is a result of making one of 90 the segments adjustable, is avoided.

Any suitable means may be provided for tilting the tool. As shown, the tool 1 is secured to the holder or head 9, against a seat provided thereon, by a pair of bolts 10 95 which thread into the tool and pass through aligned openings 11 and 12 in the head and a collar 13 interposed between the head and the heads of said bolts.

The tool holder 9 is secured to the tool 100 slide by bolts 14 which pass through slots 15 in the holder, and is adjustable vertically with reference to the slide by means of the bolt 16. The tool holder is provided on its lower face with a tapering seat 17 along 105 which the wedge 18 can be adjusted. This wedge is adapted to contact with the tool at one side of the bolts 10 so that by adjust-

ment of the wedge the tool may be rocked about an axis which extends lengthwise of the tool to change thereby the angle of engagement of the tool with reference to the 5 face of a tooth of the gear being cut, there being sufficient play between the bolts 10 and the side walls of the openings 11 of the head 9 to permit such rocking movement. The tool, however, is always rigidly secured 10 to the support by the bolts 10, since the tool contacts at one side with the holder and at the other side with the wedge.

By moving the tool, then, the pressure 15 angle of the tooth to be cut may be changed without changing the segment 7 and a result equivalent to a change in the ratio of roll, that is, a change in the segments 6 and 7 or either of them may be accomplished by the same tilting action. For the 20 purpose of insuring proper adjustment of the tool, the wedge may be provided with graduations 19, in degrees and minutes, or other angular measurement which indicates the amount it is necessary to move the tool 25 to effect a corresponding change in the pressure angle.

While I have shown a wedge as the means 30 for tilting the tool, it is obvious that any other suitable means may be employed for the same purpose; and, while I have shown my invention in connection with a machine, in which the relative roll is obtained by means of a segment fixed to the gear, rolling 35 on a relatively fixed segment secured to the frame, it is obvious that my invention is applicable to other machines of a generating character, in which other means are employed to effect the necessary generating roll and that either the tool or blank may 40 partake wholly of the generating roll or the roll may, in part, be applied to each.

While I have illustrated and described a preferred embodiment of the invention, I 45 do not desire to be restricted to the form shown since my invention is capable of modification within the scope of the invention and the limits of the appended claims.

I claim:—

1. In a machine for producing gears, a 50 tool, a blank support, means for reciprocating the tool across the face of the blank and means for adjusting the tool to vary the inclination of its cutting edge relative to

the face of a tooth to be cut to thereby vary the pressure angle of the gear being cut. 55

2. In a machine for producing gears, the combination with a blank support, a tool support, a tool mounted on said support, and means for reciprocating said tool support to move the tool across the face of the blank, of means for securing the tool to its support and means adapted to engage the tool at one side of said securing means to move the tool bodily about an axis at the other side of said securing means to vary 60 the inclination of the cutting edge of the tool relative to the tooth face to be cut.

3. In a machine for producing gears, the combination with a blank support, a tool support, a tool mounted on said support, and means for reciprocating said tool support to move the tool across the face of the blank, of means carried by said tool support and movable longitudinally of the tool to effect movement of the tool angularly 65 relative to the tooth face to be cut to thereby predetermine the pressure angle of the gear to be cut.

4. In a machine for producing gears, the combination with a blank support, a tool support, a tool mounted on said support, and means for reciprocating said tool support to move the tool across the face of the blank, of a wedge member carried by said tool support and means for adjusting said wedge 70 member to move the tool angularly relative to a tooth face to be cut to thereby predetermine the pressure angle of the gear to be cut.

5. In a machine for producing gears, the combination with a blank support, a tool support, a tool mounted on said support, and means for reciprocating said tool support to move the tool across the face of the blank, of means for securing the tool to its support 75 and a wedge member adapted to engage the tool at one side of said securing means to move the tool bodily about an axis at the other side of said securing means to vary the inclination of the cutting edge of the tool 80 relative to a tooth face of the gear to be cut.

In witness, whereof, I have hereunto set my signature.

SCHUYLER H. EARL.
